DISPENSING CABINET STRUCTURE

Earl H. Cooper, Toledo, Ohio, assignor to Jacques
Roussos, Los Angeles, Calif.

Application January 12, 1942, Serial No. 426,433

15 Claims. (Cl. 312—38)

This invention relates to towel cabinets and more particularly to a dispensing cabinet structure for intermittently dispensing or paying out predetermined or desired lengths of clean toweling from a roll or a strip or web of cloth or other material in rolled, folded or other form so as to depend from the cabinet or mechanism thereof in the form of a loop, strip or web and to simultaneously wind or take up the soiled toweling after use, and is a continuation in part of my prior application for patent on Towel cabinets, Serial No. 376,575, filed January 30, 1941.

An object of the invention is to indicate to the user the inoperative period during which the towel may not be pulled out and to continuously indicate by a discernible, perceptible or audible signal the period between the time when the towel is pulled and moved to present a clean section of toweling for use and when it may be moved again to feed or advance another clean section of toweling.

Another object of the invention is to provide means to control the feeding of the towel so that in pulling a length of toweling the feeding or measuring roll is turned other than an integral number of revolutions, thereby assuring more than one stopping position so that the pinch roll will not engage the abrasive surface of the feeding roll at the same point after each feeding operation, thereby distributing the wear over the entire abrasive surface of the roll and insuring a longer useful life for said surface and positively feeding the towel and winding or taking up the soiled towel.

Another object of the invention is to provide a novel feeding, winding, timing and time release mechanism whereby the friction feeding and winding rollers are advanced other than one complete revolution each time a length of toweling is pulled down or out for use so as to cause the strip of toweling to be engaged by pressure or pinch rollers against the friction feeding and winding rollers and to stop at different points on the surfaces of the feeding and winding rollers for every one of a multiple of operations or revolutions thereof, such as 5, thereby preventing undue wear at particular points on the friction surfaces of said rollers and increasing the useful life of said roller surfaces a multiple, i. e., five times their ordinary life.

Another object of the invention is to so arrange and support the toweling within the cabinet that practical maximum of contact areas of lengths of the toweling will be engaged with practical maximum of frictional contact areas or peripheral surfaces of the feeding and winding or take-up

rollers to also insure longer useful lives for said surfaces and more positive, uniform and even feeding and winding of the toweling.

Another object of the invention is to provide a novel mounting means for the cabinet and obviate the necessity of providing a stand or floor support, thereby releasing valuable floor space for use and obviating the possibility of the cabinet being tipped over.

Another object of the invention is to provide a novel towel cabinet which can be supported against a suitable vertical support such as a wall or board with the frame of the cabinet supporting the mechanism removable and the cover or cabinet proper hinged to its support preferably near the lower rear corner of the machine which enables it to swing forwardly and downwardly to serve as a container for holding the clean towel roll, toweling guide, soiled towel rod or roller or any other articles which might otherwise be mislaid or difficult to manipulate during the loading of the machine thereby keeping such parts readily accessible and facilitating the emptying or removal of a soiled towel roll and loading or positioning of a clean towel roll.

Another important object of the invention is to provide a pinch roll which is contained in an assembly serving as a toweling guide and made separate from the rest of the mechanism thereby permitting the positioning of the pinch roll after the toweling has been placed in position and the clean toweling roll thrown in so as to make threading of the toweling unnecessary.

Another object of the invention is to provide a novel arrangement of rollers and toweling for feeding the clean toweling from a dispensing roller to a winding or receiving roller for the used or soiled towel and to separate the clean toweling supply or roll and soiled toweling roll by a movable plate which compensates for the reduction in the size of the clean toweling supply or roll and the enlargement of the soiled toweling roll.

Another object of the invention is to provide a floating roll separator which can automatically assume any position required by the changing sizes and positions of the clean toweling supply or roll and the soiled toweling to effect a conservation of space by utilizing the space given up by the diminishing clean toweling supply or roll to accommodate the increasing size of the soiled toweling roll.

Another object of the invention is to provide a bottom for the cabinet and mechanism frame which also serves as a separator at the back to

support or receive the pressure of the clean towel supply or roll and separate the used soiled toweling from the clean toweling in passing to the winding or take-up roller and in which said separator between the clean toweling supply or roll and the ascending soiled toweling can be swung clear of the back of the machine to provide ready access thereto, thus further simplifying the task of loading.

Further objects and advantages will appear and be brought out more fully in the following specification, reference being had to the accompanying drawings, in which:

Fig. 1 is a front elevation of a roller towel cabinet in accordance with the invention.

Fig. 2 is a side elevation thereof and showing the same open in dotted lines.

Fig. 3 is an enlarged sectional elevation taken on the line 3—3 of Fig. 1.

Fig. 4 is a sectional elevation taken on the line 4—4 of Fig. 3.

Fig. 5 is a sectional view taken on the line 5—5 of Fig. 3.

Fig. 6 is a sectional elevation similar to Fig. 3 of a modification.

Fig. 7 is a sectional elevation taken on the line 7—7 of Fig. 6.

Fig. 8 is a fragmentary detail sectional elevation of one end of a friction roller.

Fig. 9 is an enlarged vertical sectional elevation of the upper portion of the cabinet immediately within one side thereof.

Fig. 10 is a sectional view taken on the line 10—10 of Fig. 9, and

Fig. 11 is a sectional view taken on the line 11—11 of Fig. 10.

Referring more particularly to the drawings in detail, 15 designates a vertical support such as a wall, board or plate mounted against or in a wall designed to support the cabinet thus obviating the necessity of employing a floor stand so that valuable floor space may be otherwise used. Secured to the vertical support 15 is a back mounting plate 16 preferably of metal having right angular or outstanding vertical or parallel side flanges 17 designed to removably support the frame or mechanism of the device. As shown, these side flanges are provided with a plurality of bayonet slots 18 opening at the top through the edges of the flanges to receive outstanding pins 19 projecting from the side plates 20 and 21 of the frame of the machine which supports the mechanism as a unit. If desired, three of such pins and bayonet slots may be provided, the pins 19 engaging the upper and lower slots and the intermediate slots being engaged by clamping screws 22 engaging threaded apertures in the plates 20 and 21 instead of providing pins 19 to engage the slots, so as to hold the frame from vertical displacement but permit removal thereof should occasion arise. The frame also includes upper and lower spacing and connecting or tie rods 23 and 24 having reduced ends forming shoulders to engage the inner faces of the side plates 20 and 21 so as to rigidly hold the same in uniform spaced relation parallel to each other with screws anchoring the ends of the rods at the outsides of the plates. The bottom edges of the plates 20 and 21 are provided with apertured ears 25 near their inner and lower corners and the cabinet or housing 26 which is shown as being substantially of rectangular form and open at the back is provided with a bottom opening 27 flanged inwardly around the bottom edge, while the cabinet may be pivoted or hinged to the mechanism

or frame near the lower rear corner of the machine to enable it to swing forwardly and downwardly to serve as a container for holding the clean towel roll, towel guide, soiled towel roll or any other articles which might otherwise be mislaid or difficult to manipulate during the loading of the machine. In the form shown, the bottom flanges or sides of the cabinet are shown provided with inwardly extending pivot pins 28 projecting in to engage the apertures of the pivot ears or lugs 25. The cabinet is sufficiently resilient to permit the sides to be separated so that the pins will spring into the apertures when the spreading pressure is released. Thus, the cabinet may be swung down beneath the frame with its open side upwardly so as to conveniently receive and retain as well as render accessible any parts placed therein. When closed, it is swung upwardly and may be held locked by any suitable means to prevent access to the interior of the cabinet. As shown, a locking screw 29 is provided in the top wall of the cabinet adjacent the open side and edge thereof which may be operated by a socket or plug wrench or key to engage the keeper or aperture of an angle bracket 30 secured to the mounting plate 16. If desired, a mirror 31 may be provided at the front of the cabinet and held at the back by a removable plate 32 over an opening in the front of the cabinet with suitable interposed cushion packing to prevent breakage of the mirror.

A bottom plate 33 is provided for the cabinet but is supported between the side plates 20 and 21 of the frame and this bottom also serves as a separator between the clean toweling roll and the ascending soiled toweling and can be swung clear of the back of the machine or back mounting plate 16 to provide ready access thereto for simplifying the task of loading as will be herein-after more fully explained. The front edge of the bottom plate 33 is shown rolled or curled up as at 34 spaced from the front wall or bottom edge of the front portion of the cabinet and at the back or rear corner is curved upwardly as indicated at 35 over the lower rod 24 to receive and support the clean towel roll when the same becomes small. This plate is then extended vertically as at 36 to form a separator or vertical partition in spaced parallel relation to the back mounting plate 16 and provide a narrow transverse vertical passage 38 therebetween through which the soiled or used towel may be passed to the winding or take-up roller, as will be later described and prevent contact thereof with the clean toweling. The top edge of the vertical plate portion 36 is provided with an angular portion 37 directed forwardly and then upwardly to frictionally spring or resiliently set under and against the upper rod 24 to hold the plate in position at the back of the frame in front of the passage or space 38. The bottom 33 is pivoted between the side plates 20 and 21 preferably in spaced relation to the rolled front edge 34 and for this purpose, may have angular brackets 39 of L-shaped form rigidly secured thereto at the top by riveting or otherwise and provided with outwardly extending pivot lugs 39a extending through correspondingly located apertures in the side plates 20 and 21. Because of this structure, the bottom plate together with the partition may be swung on the pivots so that the curled end 34 swings downwardly and rearwardly, the bottom portion 33 upwardly, and the vertical portion 36 upwardly, downwardly and forwardly so as to ex-

pose the back of the cabinet or frame when the clean towel roll is not in position.

The feeding roller is designated at F and is journaled between the plates 20 and 21 near the lower forward corners thereof and the corresponding portion of the frame, this roller being a friction or sand roll to insure gripping of the toweling T and the same as the winding roller W which forms a portion of the mechanism for the winding of the soiled toweling when the clean toweling is pulled out as will be later explained. The winding or take-up roll is designated at W and the clean towel in rolled form is designated at C, while the soiled towel roll is designated at S. An idler roller I is positioned beneath the clean towel roll C parallel to and slightly spaced rearwardly from the feeding roller F so as to take the weight of the clean towel roll when the latter is initially put into the machine to rest on the idle roller and against the vertical portion 36 of the plate which forms a separator or partition behind which the soiled towel passes upwardly in contact with the rear face thereof. The idle roller I is journaled directly in the plates 20 and 21 spaced from the bottom 33 and when the clean towel roll C becomes sufficiently small in diameter, it may pass down against the curved portion 35 between the roller I and the partition 36. A pinch roller P is positioned between the feeding roller F and the idle roller I and when in operative position, projects below the latter but is designed to be pressed against the toweling on the feeding roller F. It will be noted that the strip or web of toweling from the roll C passes over the idle roller I down under the pinch roller P, after which it passes upwardly over the feeding roller F so as to engage the frictional surface thereof over more than one-half the circumference thereof and insure positive gripping action between this roller surface and the comparatively rough surface of the toweling so that when the latter is pulled downwardly, as indicated by the arrows in Figs. 1 and 2, the feeding roller F will be positively rotated in addition to uniformly and evenly feeding the toweling. The toweling T then extends downwardly from the feeding roller F through the opening in the bottom of the cabinet between the front thereof and the curled portion 34 so as to hang in the form of a loop and then extending upwardly against the rear lower truss rod 24 in back of the partition 36 and then forwardly over and around the winding or take-up roller W for an area of over one-half the circumference thereof and then wound upon the soiled towel roller S which is mounted to be pressed toward the winding roller W as will be later explained.

The pinch roller P is contained in an assembly which serves as a toweling guide and is separable from the rest of the mechanism, thereby permitting the positioning of the pinch roll after the toweling or clean towel C has been thrown in or placed in position. For this purpose the assembly includes a pinch roller frame 40 including arcuate end plates 41 connected by tie rods 42 and also a curved guide or guard plate 43 having tongues 44 spaced along the ends thereof to engage corresponding spaced holes in the end plates 41 so as to hold the guard plate in conformity to the feeding roller above and in spaced relation thereto so that the clean toweling may pass therebetween. The plates of the pivoted assembly or frame are detachably and pivotally mounted between the side plates 20 and 21 and for this purpose may be provided with recesses 45 in the outer ends of the arcuate plates 41 and communicating

with the edges thereof to engage pivot lugs 46 extending inwardly from the side plates of the frame. The bottom edges of the end plates 41 have arcuate recesses 47 to accommodate the journals of the feeding roller F and fit around and over the same. The plates 41 are also provided with notches 48 corresponding to the notches or recesses 45 but located at the edges of the plates facing downwardly remote from the pivoted edges at the lugs 46 to engage over lugs 49 and also projecting inwardly from the side plates of the frame so that when the pinch roller assembly is mounted on the lugs 46 and swung inwardly and downwardly under the clean toweling roll C the pinch roll P will press the toweling down between the feed roller F and the idle roller I and also draw the same taut to be fed in the direction indicated by the arrows as seen in Fig. 1. The pinch roller P has a spindle 50 the ends of which engage in inclined slots 51 in the end plates 41 in tangential or divergent relation to the periphery of the feeding roller F and spaced from the adjacent end of the guard plate 43. The pinch roll has its ends journaled in hubs or spacing collars 52 positioned inside the plates 41 and coil springs 53 are fastened to the hubs or collars 52 and to the tie rod 42 at the opposite or pivoted ends of the plates 41 of the pinch roller frame or assembly and hold the pinch roller toward the feeding roller F by tending to move the same in the slots 51 toward the upper ends thereof. The top edges of the plates 41 adjacent the free ends thereof are provided with shoulders or notches 54 which are engaged by locking dogs 55 pivoted on stud pins 56 at the inner faces of the side plates 20 and 21 to hold the pinch roller frame or assembly 40 and toweling guide 43 in position. The coils of V-shaped springs 57 are mounted on the stud pins and one arm 58 hooks over the dogs 55 while the other arm 59 is anchored at one end of a segmental opening 60 in each plate so as to permit access to the dogs for releasing the same from the outside of the plates 20 and 21 whereby the pinch roller assembly may be swung outwardly on its pivots 46 and displaced from the frame. However when the pinch roller assembly is mounted on the lugs 46 and swung inwardly as previously explained, the dogs 55 will automatically engage the shoulders 54 and lock the pinch roller assembly in position.

Means may be provided for evenly guiding the toweling through the machine consisting of suitable spacing means, blocks or guides along the sides thereof at the back and shown in the form of guides 61 for the toweling to engage the side edges thereof which may be of angular formation and if desired, provided with slots to receive screws 62 for permitting adjustment to the width of the towel. A separating plate 63 is pivoted off center as at 64 on a shaft extending transversely of the plate and rigidly secured thereto so that the short side or end of the plate extends forwardly and the long side or end extends rearwardly, spaced below or under the angular portion 31 with the forward, intermediate or pivot portion resting on the clean towel roll C. This plate is pivoted at the free inner ends of a pair of opposed arms 65 closely adjacent the inner faces of the side plates 20 and 21, these arms 65 being pivoted as at 66 to said plates with screws 67 for removably mounting the arms and plate in position. The soiled towel roller S has reduced trunnions 68 journaled in open bearings or recesses 69 in the upper ends of the bearings 70 or bars 70 which have spaced flanged collars 71

adapted to slide in elongated forwardly inclined slots 72 in the side plates 20 and 21. These bearings or bars 70 are retained in position by strips or slides 73 mounted on the reduced ends of the flanged collars 71 and held by clamping screws 14. The slides 73 have outstanding angular or bent ends 75 to each of which a coiled spring 16 is anchored at one end and at the opposite end by means of screws or the like to the plates 20 and 21 of the frame as indicated at 77 so as to normally exert upward tension to press the soiled towel roller S toward the winding or take-up roller W. Each slide 73 is provided with a finger piece 78 bent therefrom to extend between the plate and a housing 79 of angular flanged construction secured to the outer faces of the plates 20 and 21 and each having a slot 80 through which said finger piece operates. Lugs 81 are provided on the side plates spaced from the lower ends of the guide ways or housings 79.

The feeding and winding or take-up rollers F and W constituting the friction or sand rollers are substantially alike in construction and each comprises a tubular cylinder or tube 82 of metal or other suitable material and provided with aligned longitudinal slots 83 near each end through which the tapered ends 84 of a spirally wound emery or sand paper strip 85 are bent, inserted and anchored, the strip being suitably anchored or glued to the cylinder if desired. The ends of the cylinder are provided with spaced segmental notches 86 equidistantly spaced apart and preferably three in number forming corresponding intermediate projections 87. Disks 88 forming webs or beads fit the notched ends of the cylinder or body and for this purpose are provided with spaced projections 89 to enter the notches 86 and corresponding notches 90 to receive the projections 87 to reinforce and close the ends of the tubes as well as connect the cylinder and disks to cause them to rotate together. The disks or webs fit snugly in the ends of the cylinders and are provided with outwardly projecting tubular flanges or hubs 91 forming spacing means between the disks and the frame members 20 and 21 and receiving shouldered tubular trunnions 92 which are keyed to the disks 88 and the hubs 91, to turn therewith. The tubular trunnions 92 are provided with two opposite flattened surfaces 93 at their outer portions and a peripheral groove 94 circumscribing the same and intersecting the flattened portions. Flanged bearings 95 are mounted on the trunnions 92 and have their flanges positioned within and against the inner face of the plate 20 adjacent the hub 91 at one side of the frame. At the opposite side a separate or removable bearing plate 96 is bolted to the plate 21 and has a sleeve or hub 97 extending into an opening 98 of larger diameter than the hub 91 as seen in Fig. 2. Screws 99 secure the plate 96 in position and a tie rod 100 extends through the roller and the tubular trunnions or bearings 92 and have their threaded ends anchored as by nuts 101 engaging threaded ends of the tie rod thus to hold the parts in assembled relation and against end thrust by engagement with the ends of the tubular trunnions or bearings 92. At one side of the frame, sprockets 102 are mounted on the flattened portions 93 of the trunnions and fixed by a set screw 103 while an endless drive member or chain 104 is trained around the sprocket wheels to cause the friction rollers to rotate in unison. They are held in position by spring cotter pins 105 which engage the annular grooves 94 at one end, pref-

erably the right side of the machine although this is optional. The corresponding end of the winding roller W is provided with a ratchet wheel 106 on the flattened portion of the trunnions 92 with its hub or collar between the plate 96 and the hub or collar of the sprocket wheel 102. At the bottom roll F there is no ratchet wheel but the collar is retained (see Fig. 4). The teeth 107 of the ratchet wheel 106 are engaged by a pawl 108 pivoted at 109 to a boss on the plate 21 and held by a spring 110 into engagement with the teeth 107 so as to prevent backward or retrograde movement of the winding roller so that the soiled towel cannot be unwound from the soiled towel roller and so that the parts can only be driven in one direction tending to feed the clean toweling and wind the soiled toweling. The ratchet wheel 106 has a spacing sleeve or hub 106a extending to the plate 96. A collar 106a is mounted to take up space on the trunnion 92 of roller F at the bottom in lieu of the ratchet wheel 106 and its sleeve or hub 106a as previously described. However, this construction permits quick removal and replacing of a friction roller by simply removing the nuts 101, rods 100 and drive parts by removing the screws 99 of the plates 96 so that the hubs 91 at one side can be displaced through the corresponding openings 98 and the webs or disks set in the ends of the body 82 displaced outwardly so that the body or cylinder can be removed and a new one inserted and secured in position. Thus, the notched construction of the friction or sand rolls 82 where the disks or webs 88 set into the ends of the body or cylinder of the roll forms axially displaceable connections between the ends of the cylinders 82 and the disks or webs 88 which enables replacement of the worn friction or sand surface by substitution of the body only with another body having a new friction or sand surface thereon, by reason of the separate bearing plates 96 at the right hand or side plate 21 and the entire removal and substitution can be effected without disassembling the machine. The tie rod construction of the assembly converts any transverse load on the sand roll hubs into a linear stress on the tie rod and not on the web assembly alone. Thus, if under extreme abuse something must give way, the resulting deformity will only be the stripping of the threads on the tie rod by failure of the cylinder and its sprocket wheel to turn together because the nuts 101 are jammed against the bearing sleeves or trunnions 92 at the threads. Thus, the hubs will be slightly loose on the trunnions 92 but not broken and the machine will not be out of service. The cost of this common type repair is reduced to just a fraction of the usual cost or entirely eliminated by this construction.

The control mechanism of the machine for the feeding, winding, timing and time release mechanism is preferably mounted at the left hand end of the lower friction or feeding roller adjacent the plate 20 at the outside and for this purpose a spur gear or pinion 111 is mounted on the flattened portions 93 of the trunnion 92 and is held in position by a spring cotter pin 112 at that side. The gear 111 is also held by keys 113 fitting the flattened portions 93 and registering recesses in the gear as shown in Fig. 2. A gear 114 meshes with the gear 111 and cooperates with other gears to intermittently check the advance of the towel feeding roller F and the timed release thereof as fully shown and described in my prior application, Serial No. 376,575, above referred to and of

which this application is a continuation in part.

In the modified form shown in Figs. 6 and 7, the construction is the same as previously described except that the lower tie rod 24a is set back slightly to receive the toweling web or strip in front thereof instead of in back as in the other form and between the same and the curved portion 35 of the bottom plate 33 to help smooth and stretch the wrinkled and damp soiled or used toweling web. The web then moves up against the plate 36 at the passage or space 38 between plates 16 and 36 and in front of and over the upper rear tie rod 24b. At this point, the upper end of the spring plate forming the vertical partition or separator 36 is bent forwardly at an obtuse angle as at 36a and this inclined top portion is curved rearwardly to form a rounded portion 37a extending upwardly and over the upper tie rod 24b on and over which the towel rides under portion 37a. Portion 37a is then bent rearwardly at its upper end, preferably substantially horizontally or slightly inclined downwardly as at 37b to receive the towel thereagainst at its rear edge which is folded or bent over or turned back that is, upwardly and forwardly over the top as at 37c to cause the toweling to scrape or slide thereon and stretch and smooth the toweling to remove wrinkles and maintain the normal length so that the depending loop will remain at a constant length and be tightly wound up on the soiled towel roll S. In this instance the toweling is extended directly to the roller S over and on the rounded portion 37a and is engaged by the friction winding or take-up roller W against the roller S to wind the toweling on the latter as the clean toweling is pulled or dispensed from the roller F. This arrangement also prevents slipping and entangling of the toweling or riding of the same upwardly in back of the rollers S or W, as where it engages directly with the friction winding roller W, due to sudden operation or pulling of the toweling from the feeding or paying out roller F, or due to sudden stopping or snapping of the toweling feed structure in checking the movement each time it is pulled.

The pinch roller assembly or frame 40 having the arcuate end plates 41 and tie rods 42, also has its curved guide or guard plate 43 extended inwardly at its inner end as at 43a to form a stop or guard extension or shelf to prevent the separator 63a from dropping down between the arcuate plate 43 or rollers F or P and the roller I when the supply C is exhausted. The shelf 43a may have cutouts or openings 43b for the springs 53. The separator plate or follower 63a is also pivoted in the center to the inner ends of the arms 65a as at 64a to balance itself and the arms 65a are longer than the arms 65 in the other form. Also, the plate 36 has keeper openings or slots 36b near the opposite edges thereof to engage or spring over notched catches 36c in the form of notched bars or posts outstanding from the plate 16 and having beveled inner ends or noses as shown so that the plate 36 will spring down under the catches at the openings and snap into the notches 36c. The catches 36c may be secured to the plate 16 by base flanges 36d secured by welding, riveting or otherwise to the plate 16. A handle 36f is also attached centrally to the plate 36 to press down on the latter to disengage the catches from the openings 36b or for engaging the same after the toweling is passed around the roller S. The pivoting of the plate 33 so that part 36 can swing down and forwardly obviates the

necessity of threading the toweling web or strip so that a machine or cabinet can be loaded or reloaded in a jiffy.

Operation

- 5 In the operation of the device, assuming that the cabinet is empty of toweling, the housing or cabinet proper is released by turning the locking screw 29 to disengage it from the bracket or keeper 30 whereupon it may be swung 90 degrees 10 forwardly and downwardly on the hinged connection or pivots 28 against the vertical support 15 below the mechanism with the open side which normally fits or is disposed toward the vertical support at the back disposed upwardly and the open bottom at the rear or back so that the side, top and front walls of the cabinet will form a receptacle for receiving a roll of clean toweling. It will also serve as a container for the toweling guide or pinch roll assembly 40 which is removed 15 from its operative position by swinging it upwardly on the pivots 46 and removing it from the frame. It will also support the soiled toweling roller S or any other articles which might otherwise be mislaid or difficult to manipulate 20 during the loading of the machine. The soiled toweling roller S is merely displaced from the open bearings or recesses 69 in the upper ends of the bearings 70. A length of clean toweling T is then unrolled from the clean towel roll C and with the plate 33 swung on its pivot so as to dispose the partition or separator 36 forwardly and downwardly relative to its normal vertical position where it forms the space 38 in connection with the back mounting plate 16, the end of the toweling is then passed under the bottom of the machine in back of the rods 24 through the space 38 which has been opened by the forward tilting of the plate portion 36 so as to render accessible 25 the back of the machine to facilitate loading. The fact that the bottom of the cabinet is integral with the separator which is normally positioned between the clean toweling roll and the ascending soiled toweling and can be swung clear of the back of the machine to provide ready 30 access thereto greatly simplifies the task of loading. The toweling is then extended over or under the winding or take-up roller W and the end portion thereof wound upon the soiled towel roller S which is placed in position in the bearings 70 and pressed against the roller W by the tension of the springs 76. The plate 33 is then swung back into position with its vertical portion or partition 36 in front of the ascending toweling where it is held by the angular portion 37 frictionally and resiliently engaging the upper rod 24. With sufficient length of the clean towel depending below the machine in the form of a loop as shown in Figs. 1 and 2, the length of which may be varied 35 as desired, the clean roll of toweling 6 is then thrust or placed in position as shown in Fig. 1 resting upon the idle roller I and the partition or separator 36 spaced above the bottom portion 33. The separating plate 63 which automatically 40 floats with the pivoted arms 65 may be raised to facilitate insertion of the clean towel roll and will move down as the clean toweling is dispensed therefrom but normally may assume the position shown in Fig. 3 but always keep the soiled toweling out of contact with the clean toweling continuously during the time when the latter is unwound from the roll C and being wound on the roller S. The pinch roller and guide assembly or frame 40 is then inserted in 45 position by engaging the notches 45 with the

pivots 46 and swinging the same rearwardly and downwardly on said pivots over the feed roll F so that the pinch roller P will frictionally engage and press in the toweling on roll C to pass or snap by the periphery of the clean toweling roll C and move below the idle roller I permitted by the slots 51 in which the spindle 50 of the pinch roller P is journaled and the normal tendency of the springs 53 to hold the pinch roller at the inner ends of the slots. The placing of the clean toweling roll C in position as previously explained will cause the toweling T to pass over the feeding roller F and the idle roller I so that when the pinch roller assembly is placed in position as just described, the pinch roller will loop or press the toweling downwardly by pressure thereon between the idle roller I and the feeding roller F and will place the pinch roller and toweling under tension by pressure against the feeding roller F from the springs 53 due to the inclination of the slots 51 and the tangential relation or convergency thereof toward the periphery of the feeding roller F and the tendency of the springs 53 to press or hold the pinch roller against the feeding roller F and toweling thereon below its axis 100 and at the same time the guard plate or guide 43 will be positioned over the feeding roller and the assembly or frame held in position by engagement of the notches 48 with the pins or lugs 49. The pinch roll is contained in an assembly which serves as a toweling guide and is separable from the rest of the mechanism thereby positioning the pinch roller after the toweling has been thrown or placed in position. This makes threading of the toweling unnecessary. Also, owing to the fact that the pinch roller is positioned under spring tension, no toweling slippage is required to set the pinch roller firmly and in position pressing against the feeding roller with the interposed toweling. Most, if not all other machines, require motion of the toweling to accomplish this function. The machine is now ready to operate and when a clean wiping section of toweling is desired, the user merely grasps the clean toweling depending below the machine at the open bottom below the feeding roller F and adjacent the curled portion 34 and a downward pull is exerted thereon. Due to the frictional engagement of the toweling with the feeding roller F, the latter will be rotated as well as the pinch roller P and the idle roller I to unwind the toweling from the clean toweling roll C. Due to the feeding and winding rollers being positively connected by the chain 104 on the sprocket wheels 102, the winding or take-up roller W will be rotated in the same direction as the feeding roller F thereby advancing the soiled toweling around the winding roller and causing it to be wound on the soiled toweling roll S by reason of the latter and the toweling thereon being pressed against the winding roller W by the springs 76 which elevate the bearings 70 in the slots 72. By holding the soiled toweling roll in contact with the take-up or winding roller by spring tension instead of depending upon the gravity as in most, if not all other machines, this produces a more uniformly and tightly wound roll of soiled toweling, thus reducing the space requirement of the roll. The floating separator or plate 63 which can assume any position required by the changing sizes and positions of the toweling rolls is used to effect a conservation of space by using the space given up by the diminishing clean roll to

accommodate the increasing size of the soiled toweling roll.

In order to regulate the feeding or advancing of the toweling as well as the winding and the time interval of the perceptible or discernible signal which, as explained in my prior application, Serial No. 376,575, heretofore referred to herein, is audible in this instance due to the buzzing sound of the operation of the gears of the timing or clock mechanism 115 and thus indicate to the user when the device is inoperative or when the toweling may not be pulled out, as well as give an audible, discernible or perceptible signal continuously during the period when the toweling is normally used for the wiping operation or the period while held between the time when the toweling is pulled or moved out and the time when it may be moved again, the following operation takes place. When the toweling is pulled to rotate the feeding roller F and the winding roller W, the latter will be permitted to rotate by the pawl 108 riding over the teeth of the ratchet wheel 106 but restraining the same against reverse rotation so that the toweling cannot be unwound from the soiled toweling roll. By reason of the novel ratio of feeding, winding timing and time release mechanism, whereby the friction feeding and winding rollers are advanced other than an integral number of revolutions each time a length of toweling is pulled down or out for use and arranging the toweling so as to cause the strip of toweling to extend around or engage with the friction surfaces on said rollers at the major or practicable maximum portions of their peripheries, but more particularly by causing the engagement of the pinch roller P with the roller F as well as the soiled toweling roll S with the winding or take-up roller W at a different point on the periphery of the feeding and winding rollers respectively when stopped after each cycle of operation or moving of the toweling to advance a clean section to wiping position thereby preventing undue wear on the friction surfaces on said rollers at any particular point as where the same point on the roller F stops in confronting position to the pinch roller P or one point on the winding roller W stops in confronting position to the soiled toweling roll S at each operation, increase in the useful life of the roller surfaces is insured. In the particular arrangement shown, a different surface will be presented to the pinch roller for every multiple of four operations before repeating and before the same point is again contacted thereby preventing undue wear on the friction surfaces, emery paper or sand paper of the friction or sand rollers constituting the feeding and winding rollers and increasing the useful life of said roller surfaces a multiple of or approximately four times their ordinary life. The construction of the means for supporting and feeding the clean toweling as well as winding up the soiled toweling, the arrangement of the rollers and the manner in which the toweling is run through the machine as well as the construction of the rollers for feeding and winding up the toweling and the arrangement of the pinch roller P and the soiled toweling roll S held under constant spring pressure against the respective feeding and winding rollers F and W respectively insure uniform, even and positive feeding and winding of the toweling as it moves down at the front and up at the back. This is also due to the fact that the soiled toweling roll is held in contact with the take-up or winding roll by spring

tension instead of depending upon gravity as in most, if not all other machines, thus not only producing a more uniformly and tightly wound roll of soiled toweling but also reducing the space requirement of the roll. The pinch roll is also contained in an assembly or frame which serves as a toweling guide by reason of the opposite edges of the toweling strip feeding between the end plates 41 thereof and between the feeding roll and the guide plate 43 which is disposed in spaced concentric or parallel relation thereto. By having the pinch roll assembly separable from the rest of the mechanism, the pinch roll may be placed in position after the toweling has been mounted in position, thus making threading of the toweling between rollers I, P and F unnecessary. Placing of the toweling is also facilitated especially due to the fact that the separator or partition formed by the vertical wall 36 may be swung down away from the back of the machine when the end of the toweling is first wound upon the soiled towel roller S after being passed over and around the winding roller W and then fastened to or wound upon the winding roller S. By having the pinch roll pressing against the feeding roll under spring tension and positioned or snapped in position under such tension over the feeding roller and under the clean towel roll so that the toweling is looped down between the idle roller I and the feeding roller F by the pinch roller P when in position as more particularly shown in Fig. 1 of the drawings, no towel slippage is required to set the pinch roller firmly. The toweling is maintained in constant uniform contact under pressure with a maximum surface or more than half the circumference of the feeding roller F as well as in engagement with the idling roller. This is also true of the engagement of the toweling with the winding roller W over more than one-half the circumference thereof which is further insured by the pressure between the toweling on the soiled towel roller S and the periphery of the winding roller W due to the resilient mounting of the soiled towel roller and the action of the springs 16 in maintaining the roller S and the soiled toweling wound thereon against the surface of the roller W by means of the spring held bearings 10. The separators 36 and 63 also maintain the clean toweling out of contact with the soiled toweling and the latter separator compensates for the varying sizes of the clean and soiled toweling rolls. By reason of the floating action thereof so that the separator 63 can assume any position required by the changing sizes and positions of the toweling rolls, a conservation of space is effected by utilizing the space given up by the diminishing clean roll to accommodate the increasing size of the soiled towel roll and when the clean towel roll is sufficiently small it may drop between the idle roller I and the vertical plate 36 on to the bottom 33 while still pressing against the idle roller I and increasing the surface contact with the latter until entirely unwound and paid out. At this time the bearings 10 may be depressed and the soiled towel roll displaced and removed by disengaging the trunnions 68 from the bearings 10 at the open recesses 69 when the machine is again in condition for reloading in the manner previously described. It should also be noted and will be apparent from the foregoing description of the construction and operation that due to the feeding and winding rollers being of the same diameter, operatively connected as described and

directly controlling the feeding and winding of the towel in addition to the means for preventing retrograde movement or unwinding of the soiled toweling roll, the soiled toweling will be rolled up into the cabinet in the form of a roller at a linear rate exactly equal to the linear rate at which the clean toweling is uniformly dispensed or pulled out according to the adjustment for which the machine is set but preferably approximately eight inches, thus keeping the amount or length of the depending loop of exposed toweling substantially constant. It will also appear that while the length of toweling dispensed at each use is preferably eight inches, this may be adjusted or varied as desired, as by varying the sizes of the feeding and winding rollers and the gear ratio of the driving means or gearing train, so that each successive length of toweling dispensed shall be and remain uniform once an adjustment is made. Also, the operating parts, device or feed roller and the toweling are locked or held against movement after each pulling of the towel and the toweling prevented from slipping when pulled unnaturally hard or in normal operation, thereby preventing rewinding of the used or soiled toweling on the clean toweling roll or unwinding the used or soiled toweling from the soiled toweling roll. Also, the time interval feedings may be controlled by the time controlled mechanism 115 which may be adjusted as desired, say from five to twenty-two seconds or otherwise. The time controlled mechanism as well as all the other mechanisms, is not accessible to any one using the machine by reason of being enclosed in the cabinet in the manner described thus preventing tampering therewith and rendering the device fool-proof.

It may also be stated that by having the damp used toweling pass upwardly against the lower tie rod 24 and the separator or plate 36 under angular stress at the top and bottom, the damp toweling is smoothed flat instead of leaving the same folded, rumpled or uneven and free to shrink. This is assisted by placing the toweling under pressure and tension of the depending loop and pulling thereon in dispensing or pulling the toweling out or down for and in use, and in the toweling being wound or taken up on the roller W and the roll S, as well as the frictional engagement and sliding of the toweling against the rear lower truss rod 24 or the plate 36, whereby the toweling will be kept smooth and somewhat stretched out to normal condition or length and assisted in drying, so that the depending loop or length of toweling for use will be maintained in a loop of constant length, instead of shortening by drying in a crinkled, wrinkled, folded or uneven condition.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

Having thus described my invention, what I claim as new and desire to secure by Letters Patent is:

1. In a towel dispensing device of the class described, a vertical support, a housing hinged to the support at the bottom and open at the bottom and back thereof, towel holding and feeding

means secured to the support independent of the housing to partially close said bottom and provide openings at the front and back to receive the towel therethrough and adapted to feed the towel through the open bottom of the housing, said housing adapted to swing down against the vertical support free of the towel feeding means to form a receptacle and means to lock the housing over the feeding means against the support to close the back of the housing.

2. In a towel cabinet, a lower feeding roller, a pinch roller coating therewith below the center of the feeding roller at one side, a towel support in spaced relation to the feeding roller from which the towel passes between the feeding roller and the pinch roller under the pinch roller and over the feeding roller, and the pinch roller adapted to pass down against the towel between the towel support and the feeding roller to form a bight in the toweling and take up slack, said towel depending from the cabinet and extending upwardly at the back of the cabinet, a winding roller over which the upwardly extending portion of the towel passes and a soiled towel roller on which the soiled towel is wound, said soiled towel roller being held under pressure against the towel and winding roller.

3. In a towel cabinet, a lower feeding roller, a pinch roller engaging the feeding roller at the lower part of the receiving side thereof, a towel support from which the towel passes over the feeding roller and under the pinch roller, said pinch roller being adapted to be placed in position between the support and feeding roller over the towel after the latter is passed over the feeding roller, said towel depending from the feeding roller and cabinet and extending upwardly at the back of the cabinet, a winding roller, a soiled towel roller, the soiled towel passing between the winding and soiled towel rollers to wind on the latter, means for removably supporting the soiled towel roller and urging the same upwardly in pressure contact with the winding roller, and means for separating the soiled toweling from the clean toweling.

4. A towel cabinet adapted to be mounted on a vertical support including a back plate secured to said support, a frame on said back plate, a cabinet thereover open at the bottom, a plate pivoted in spaced relation to the front thereof at the bottom of the frame, forming the sole bottom of the cabinet and having an upwardly extending portion forming a partition in spaced relation to the backplate at the back of the cabinet, towel feeding means at the front and lower portion of the frame, means to support a clean towel roll at the lower portion of the frame, said towel passing up in back of the partition, soiled towel winding means at the top and back portion of the frame, means for actuating the winding means including a friction roller for causing the used toweling to be so wound during the feeding of the clean toweling as to cause the toweling to depend in a loop of constant length.

5. A towel cabinet having a bottom wall pivotally hung on means in the cabinet at a point spaced from its front edge and an opening at the front thereof through which a towel is adapted to be drawn, a roller above the pivot of the bottom wall, said bottom wall having a rear portion extending upwardly in spaced relation to the back of the cabinet to receive a clean toweling supply roll thereon against the front surface of said rear portion in conjunction with said roll-

er and adapted to support said supply roll at the bottom when the size of the roll is reduced and to accommodate soiled towel extending upwardly through said second-mentioned space and means for winding the soiled toweling.

6. In a towel cabinet, a lower feeding roller, a pinch-roller frame removably mounted over and conforming in shape to the feeding roller and including a pinch roller movably journaled in the frame and engaging the feeding roller at the back and below the axis thereof, a towel supply roll support from which the towel passes downwardly under the pinch roller and then upwardly between the feeding roller and the pinch roller, said towel then passing over the feeding roller, depending therefrom and extending upwardly at the back, a winding roller and a soiled towel roller on which the soiled towel is wound and means to hold said soiled towel under pressure against the winding roller, said towel passing forwardly under and around the soiled towel roller.

7. A towel cabinet adapted to be mounted on a vertical support including a removably mounted frame, a vertical plate having side flanges, said frame having side plates, pin and bayonet slot connections between the side plates and flanges, a cabinet thereover having a bottom opening, a back plate forming a partition in spaced relation to the vertical plate at the back of the cabinet, upper and lower rods across the frame adjacent the back thereof against and over which the towel passes, towel feeding means at the front and lower portion of the frame, means to support a clean towel roll at the lower portion of the frame, said towel passing up in back of the partition, a winding means for winding the toweling as used above the clean towel roll and simultaneously and at the same rate with the feeding thereof.

8. A towel cabinet adapted to be mounted on a vertical support including a frame having sides mounted on the vertical support, a cabinet thereover having a bottom opening, a back plate supported by the sides forming a partition in spaced relation to the vertical support at the back of the cabinet, upper and lower rods across the frame against and over which the towel passes, the top of the back plate being extended forwardly and up in front of the upper rod to allow the towel to pass in front of the rod, towel feeding means at the front and lower portion of the frame, means to support a clean towel roll at the lower portion of the frame, said towel passing up in back of the partition, a winding means at the top and back portion of the frame and means actuating the winding means for winding the toweling as used above the clean towel roll and simultaneously and at the same rate with the feeding thereof.

9. In a towel cabinet, a towel supply, towel feeding means, towel winding means, a plate mounted in the cabinet and extending upwardly, a rod over which soiled towel passes, the top of the plate being extended forwardly and rearwardly over the rod and the towel being passed over the rear edge of the rearwardly extended portion to smooth and stretch the towel and then forwardly to the winding means to wind thereon.

10. In a towel cabinet, a feeding roll and a winding roll, a lower clean towel roll, an upper soiled towel roll and a centrally pivoted floating separator mounted in the cabinet and positioned between said clean and soiled towel rolls.

11. In a towel cabinet, a frame a back wall, a bottom wall with an upwardly curved rear portion forming a passage with the back wall through which the towel is adapted to pass, an idle roller across the lower portion of the cabinet upon which a clean towel supply roll is adapted to rest in conjunction with the upwardly extending portion, said roll adapted to be supported on the bottom wall between the idle roller and the rear portion when the roll is reduced in size, a friction feed roller in front of said idle roller for receiving the towel thereover after passing over the idle roller, a pinch roller frame mounted in the first named frame over the feed roller and provided with towel guide means, a pinch roller held in the pinch roller frame below the idle roller and pressed against the feed roller below the axis thereof, and means for receiving and winding the soiled towel as clean towel is unwound from the supply roll and drawn downwardly over the feed roll and beneath the front of the cabinet.

12. In a towel cabinet having front and back walls, a frame, a bottom wall with a rear portion extending upwardly in spaced relation to the back wall of the cabinet to form a passage therewith, an idle roller across the lower portion of the cabinet upon which a clean towel supply is adapted to rest in conjunction with the rear portion initially and until reduced in size, said bottom wall being pivoted near the front thereof, a friction feed roller in front of said idle roller for receiving the towel thereover, a pinch roller frame removably mounted over the feed roller and having a top portion and side portions to guide the toweling over the feed roller, a pinch roller resiliently supported in the pinch roller frame and pressed toward the feed roller to retain the towel taut between the idle roller and the feed roller and under which the toweling is adapted to pass from the idle roller, against the feed roller and over the latter to depend at the front of the cabinet and form a loop therebeneath and then to extend upwardly through the passage, an upper friction winding roller and a soiled towel roller resiliently supported against the winding roller to wind the soiled towel thereon.

13. A towel cabinet adapted to be mounted on a vertical support including a frame having sides mounted on the vertical support, a cabinet thereover having a bottom opening, a back plate forming a partition in spaced relation to the

vertical support at the back of the cabinet and having a forwardly extending bottom portion pivoted intermediately to the sides of the frame, upper and lower rods across the frame in rear of the partition and against and over which the towel passes, the top of the back plate being extended upwardly and forwardly in front of and over the upper rod in spaced relation thereto to receive the toweling between the rod and portion of the back plate extending over the rod, towel feeding means at the front and lower portion of the frame, means to support a clean towel at the lower portion of the frame in conjunction with the back plate and bottom portion thereof, said towel passing up in back of the partition, winding means at the top and back portion of the frame and cabinet and means actuating the winding means and pressed against the latter with the towel therebetween for winding the toweling as used.

14. In a towel cabinet, a cabinet having a soiled towel roll having trunnions, a friction roller adjacent said roll, side members in the cabinet, inclined housing supported in the cabinet on the side members thereof, said side members having slots, movable open top bearings having portions in the slots and movable within the housings, said bearings supporting the trunnions of the soiled towel roll, said bearing portions being projections movable in the housings, and springs in the housings connected to the side members and to the projections therebeneath and supporting the bearings to press the soiled towel roll against the adjacent friction roller.

15. A towel cabinet adapted to be mounted on a vertical support including a frame having sides mounted on the vertical support, a cabinet having a bottom opening, a back plate forming a partition in spaced relation to the vertical support and having a forwardly extending bottom portion pivoted intermediately to the sides of the frame, upper and lower rods in rear of the partition across the frame, the top of the back plate being extended forwardly and up in front of the upper rod, towel feeding means at the front and lower portion of the frame, means to support a clean towel roll at the lower portion of the frame in conjunction with the bottom portion of the back plate, said towel passing up in back of the partition, winding means at the top and back portion of the frame, and means actuating the winding means for winding the toweling as used.

EARL H. COOPER.
